OTTO THIEME, OF ST. LOUIS, MISSOURI, ASSIGNOR TO MOON-HOPKINS BILLING MACHINE COMPANY, OF ST. LOUIS, MISSOURI, A CORPORATION OF MISSOURI.

PRINTING MECHANISM.

1,294,196.

Specification of Letters Patent. Patented Feb. 11, 1919.

Original application filed May 20, 1916, Serial No. 98,853. Divided and this application filed March 27, 1918. Serial No. 224,956.

To all whom it may concern:

Be it known that I, Otto THIEME, a citizen of the United States, residing at the city of St. Louis, State of Missouri, have invented a certain new and useful Improvement in Printing Mechanism, of which the following is a full, clear, and exact description, such as will enable others skilled in the art to which it appertains to make and use the same, reference being had to the accompanying drawings, forming part of this specification, in which—

Figure 1 is a vertical sectional view illustrating my improved printing mechanism as used in connection with calculating machines.

Fig. 2 is a top plan view of the same;

Fig. 3 is a view illustrating the motor drive connection.

Fig. 4 is a view illustrating the means operated by the traveling carriage for connecting the printing mechanism to the motor.

Fig. 5 is a detail side elevational view of said locking means.

Fig. 6 is a sectional view on line 6—6 of Fig. 5.

Fig. 7 is an end elevational view partly in section of a carriage operated part.

Fig. 8 is a detail view illustrating a part of the ribbon feeding mechanism.

Fig. 9 is a view of the paper feeding mechanism.

Fig. 10 is a detail view of one of the printing segments showing the ribbon guiding arm.

Fig. 11 is a detail view illustrating the ribbon guiding arm in cross section.

Fig. 12 is a detail view illustrating the means for controlling the zero printing type.

Fig. 13 is a rear elevational view illustrating the ribbon feeding mechanism.

Fig. 14 is a detail view illustrating one of the racks which controls the position of the printing elements.

Fig. 15 is a top plan view of the ribbon feed for one of the printing mechanisms.

Figs. 16, 17, 18, and 19, are detail views of the several blocks carried by the paper carriage.

Fig. 20 illustrates the blocks mounted on the bar of the carriage.

Fig. 21 is a diagrammatic view of a modi-

fied form of control for the tally-roll as operated by the total key.

Fig. 22 is a similar view showing the manner of control of the tally-roll as operated by the rear total key.

Fig. 23 is a rear elevational view of part of the tally-roll carriage showing the tabulating bar.

Fig. 24 is a top plan view of a combined adding and typewriting machine to which my improved printing mechanism is attached.

This invention relates to a new and useful improvement in printing mechanisms designed especially for use in connection with calculating machines. The present application is a division of an application filed

by me May 20, 1916, serially numbered 98,853, which application related to a tally-roll attachment for calculating machines, the object being to provide a plurality of means whereby comprehensive statements of

various transactions and operations performed by the machine may be recorded on different sheets or strips of paper. For instance, in the making up of statements for

country banks, or customers, whether daily or monthly, it is the practice to distribute various items constituting said statements in different columns where they may be checked over by the bank and its customers.

The statement is usually sent to the customer. It is desirable that, at the time of preparing these statements to be issued to the customers, the bank retain a record

thereof for its own use in order that at the end of the day or whatever period is covered by the issued statements, the bank will have a complete record of the issued statements for purposes of re-checking and correcting errors in the issued statements should any be found to exist.

To illustrate a customer's statement:

Date.	Checks.	Date.	Checks.	Date.	Deposits.
March 1	25.00	March 19	250.00	March 1	500.00
3	75.00	13	350.00	5	300.00
5	100.00	18	200.00	15	650.00
7	250.00	23	100.00	25	86.00
	450.00		900.00		Footings 1,807.56
					Checks returned..... 1,350.00
					Bal. March 31 ..... 457.56
				Total.....	1,807.56

This statement is made up in the usual

- way on the regular slips issued by the bank at the time the customer's book is balanced and shows two or more columns, the dates and amounts checked out on the said dates, 5 the old balance, or balance forwarded, the amount of deposits, the total of checks returned, the balance on the day the statement was issued, and total of the old balance, plus the deposits which equal the new balance as 10 determined by subtracting the checks returned from the total of the old balance and deposits.

The tally roll in the present machine is designed only to show the figures printed by 15 the adding mechanism or the various totals, and for the purpose of identification, the operator should indicate the customer's number, at the top of the statement, which number is, of course, not added in the accumulators. To illustrate the use of the tally-roll attachment in sending out daily statements to country banks, the following may be given as an example:

	<i>Old bal.</i>	<i>Deposits.</i>	<i>Checked out.</i>	<i>Ex-change.</i>	<i>New balance.</i>
	1,234.50	3,500.00	3,675.00	4.50	1,055.00
	1,075.00	6,000.00	5,000.00	6.00	2,069.00
	2,546.00	100.00	1,900.00	.50	745.50
	4,855.50	9,600.00	10,575.00	11.00	3,869.50

- 30 In some instances, in making up bank statements, it is desirable, for checking purposes, to record each item comprising the totals of the different columns, and these may be obtained by the use of the adjustable blocks to be hereinafter described. In other instances, it is desirable only to obtain the totals of the various columns appearing in the statement to be issued, in which event such totals may be controlled by the several 40 total keys of the machine, the adjustable blocks on the main paper carriage being moved to one side, or entirely removed, if this latter operation is desired.

In the drawings, I have shown a combined 45 typewriting and adding machine such as is disclosed in French Patent No. 383,719, dated January 16, 1908, and which is also shown in application for United States Letters Patent filed by Hubert Hopkins, Serial No. 310,739, filed April 9, 1906, to which my tally roll attachment is applied; but it is obvious that the principles of operation hereinafter described and the mechanism for carrying the same into effect may be utilized 55 with other types of machines.

In the following description, I shall utilize, as far as practicable, the same reference numerals which are applied in said French patent to refer to corresponding 60 parts. I will state, however, that in the present machine the multiplying mechanism and associate parts have been omitted, but the wheels 268, which form the product-wheels in multiplying operations of the 65 mechanism disclosed in the French patent,

have been retained. In the present machine they are only used as adding wheels; however, the multiplying mechanism may be retained if desired.

Typewriter mechanism.

I have not disclosed all the details of the typewriter mechanism in this case as it is only necessary to state that the printing type carried by the forward ends of the racks 75 make an impression on the paper supported by the platen of the laterally movable carriage. The main paper carriage has mounted thereon and movable therewith, a notched rack 39, on which notched rack are 80 adjustably mounted various stops, to be hereinafter described, for controlling different parts of mechanisms of the adding department of the machine. Preferably there is provided tabulating mechanism for this 85 main paper carriage, means for operating the escapement of said carriage to letter-space the same when a digit key in the adding department is operated, means for preventing lateral movement of the carriage 90 when a digit key of the adding department is operated so that the adding department may record various items in column order, means for line-spacing the platen of this carriage upon the operation of the adding 95 mechanism, etc., all of which are described in said French patent, before referred to, and therefore need not be specifically described here.

The totalizers.

These consist of two sets of wheels 119 and 268 mounted in frames which are movable so as to engage and disengage the totalizer wheels with the racks 100 whereby, 105 when said racks make an excursion, they will not only position the printing type both front and rear, but will register the numbers printed in one or the other set of totalizer wheels depending upon which is selected to 110 receive such number. The means for controlling the excursions of the racks comprising the setting-up mechanism operated by the keyboard of the adding mechanism, forms no part of the present invention, nor 115 is it necessary to describe the carrying mechanism and its manner of control, as these or equivalent parts are fully disclosed in said French patent.

Tally roll frame.

Referring now to Figs. 1, 2 and 3, it will be observed that the casing 500, which encloses the rear end of the machine, has two brackets 501 mounted thereon, which brackets extend rearwardly and provide supports for a grooved shaft 502. 503 indicates the frame consisting of two side arms which are provided with bearings so that said frame may slide longitudinally on the shaft 130

502, and a cross arm on whose upper edge is secured a serrated plate 504 forming a tearing edge for the tally strip, and on the inner face of which cross arm is mounted a 5 platen 505 of rubber or other suitable material. This frame 503 forms a support for the paper guides 506 and 507 and also a mount for the paper feed rolls 508 and 509, the former of which is preferably idle. 510 10 is a cross bar connecting the lower legs of the frame to which is secured a plate 511 operating in the groove of shaft 502, said plate having some play in said groove so as to provide lost motion, the purpose of which 15 will hereinafter be described. 512 indicates a frame having upward extensions bent to embrace the shaft 502, said extensions being located within and adjacent the legs of the frame 503 so that the frame 512 will 20 be moved in all positions of the frame 503. Frame 512 has side members 513 preferably bent outwardly therefrom, the upper ends of which side members provide a support for a guide roller 514 for the paper, and the 25 lower ends of which side members provide a mount for the spool 515 which carries the roll of paper 516 from which the tally strip 600 is fed. 517 indicates a bail mounted on the frame 512 and held against the tally 30 strip by means of a torsion spring 518, the purpose of this being to exert a braking action upon the tally strip so as to keep it taut as it is being unwound from its supply roll. An inward extension on each side 35 frame 513 carries a roller 519 which bears upon a track plate 520 secured to the rear wall of the casing of the machine and extending parallel to the rear wall thereof and entirely across said rear wall, as shown. 40 The frame 503 carries an escapement rack 521 below the shaft 502, on which rack is a depending portion carrying a roller 522 which bears on the outer face of track plate 520 (see Figs. 2 and 3). By means of this 45 roller 522, the upper end of frame 503 is permitted to move forwardly so that its platen 506 can make a printing impression, such forward movement of frame 503 not disturbing the frame 512; and likewise, the 50 lower end of frame 512 is permitted to move outwardly slightly if for any cause the tension on the tally strip is such as to require such movement. This outward movement of the lower end of frame 512 is also desirable in introducing a new roll of tally 55 paper.

In order to hold the frame 503 in the position shown in full lines in Fig. 1, I pivotally mount a bar 523 on the lower edge of 60 the track rail 520, the upper end of which bar carries a roller 524 which bears against the outer face of the escapement bar 521 so as to normally hold said bar and frame 503 which carries it in the full line position 65 shown in Fig. 1. The spring 525 connected

to the rod 523 at all times holds the roller against the escapement bar and tends to move the same inwardly so the said bar and frame will occupy their normal positions.

Tally roll frame escapement.

70

Reference has been made heretofore to the printing of different numbers on the sheet of paper carried by the main paper carriage in column order and horizontal alignment, which numbers, as the typewriter carriage is advanced leftwardly, through the medium of the adjustable blocks 40, causes certain of said numbers, in at least three of the columns, (or such number of 80 separate accumulators as may be arranged upon the shaft 48) to be separately accumulated.

75

Assuming now that it is desirable to make a record on the tally strip of the different 85 items constituting the three columns registered and accumulated in the groups of forward totalizer wheels 119 (or the totals thereof), it follows that, as the typewriter carriage advances leftwardly, and, through 90 the blocks 40 carried thereby, operates the escapement so as to successively bring the groups of totalizer wheels 119 under control of the racks 100, the tally-roll carriage, whose starting or home position, like the 95 typewriter carriage, is at the right of the machine, looking from the front, will have to be stepped leftwardly so as to present different printing surfaces of the tally-roll to the recording mechanism so that the tally-roll will have corresponding columns of 100 figures or totals thereof impressed thereon. The frame 503, before referred to, has a spring 526 (see Fig. 23) connected thereto, (the right hand end looking from the front 105 of the machine), the other end of the spring being connected to one of the brackets 501 so that the energy of said spring is at all times exerted to draw the frame 503 leftwardly, with respect to the operator standing in front of the machine. 110

The escapement bar 521, carried by the frame 503, is provided with a series of recesses 521^a and projections 521^b located according to the desired stepping movement 115 of the frame, with which recesses and projections co-operates an escapement pawl 527 (see Fig. 23) in the form of a bell crank lever, said escapement pawl being pivoted to a bracket 530 extending inwardly from the 120 track rail 520. This track rail is cut away or recessed to permit the operation of the escapement pawl. The escapement pawl has a leaf spring member 527^a secured thereto and whose free rear end co-operates with the 125 projections 521^b on the escapement rail, the purpose of this spring 527^a being to absorb the shock of the tally roll carriage. I do not in this application claim the construction and arrangement of this escapement 130

mechanism and do not deem it necessary to further describe the same in detail, as it is fully illustrated and described in the parent case filed May 20, 1916, Serial No. 98,853.

5 531 represents a bar slotted at each end to engage screws which find a bearing in some suitable frame members of the machine, (see Fig. 2) whereby, through the medium of these guiding slots, the bar 531 may be 10 moved rearwardly into engagement with the escapement pawl to depress the rear end of the same out of the path of its coöperating projection 521^b on the escapement rail 521. Bar 531 is held forwardly by means of a 15 spring 532. A tappet 533 is mounted upon the extreme forward end of the bar 531 to coöperate with adjustable blocks 534 mounted upon the notched rail 39 of the typewriter carriage. These blocks 534 have piv- 20 oted members 535 mounted thereon similar to the pivoted members 42 of the blocks 40, except that the rear ends of these pivoted members 535 lie in a different horizontal plane (see Fig. 20). In this manner, the 25 different stop blocks on the notched bar 39 may coöperate with their respective tappets without interference with other tappets. The front end of tappet 533 is beveled or inclined as shown in Fig. 2 so that as the 30 typewriter carriage moves leftwardly, in the direction of the arrow, on bar 39, the members 535 will engage the inclined end of the tappet 533 and cam the same rearwardly. Upon the return movement of the typewriter carriage to the right, the tappet 533 swings on its pivot in a manner well known 35 without vibrating the bar 531.

Returning the tally-roll carriage.

40 In United States Letters Patent No. 1,120,862, granted December 15, 1914, upon an application for improvements in carriage return mechanism filed by me, I have shown a construction for returning the typewriter carriage from a constantly rotating motor shaft, this carriage return mechanism being rendered effective by the depression of what is known as a carriage return key. In the drawings, (see Figs. 2 and 3), 535' is a 45 constantly running shaft driven from the motor drive of the machine, the upper end of which shaft has clutch connection with the lower end of a normally idle shaft 539. The upper end of this normally idle shaft 50 carries a gear wheel 542 which is designed 55 to mesh with rack teeth 543 formed on the inner face of the escapement bar 521. The carriage return mechanism, including the gear wheel 542, is mounted in the frame of 60 the machine, while the escapement bar, having the rack teeth which mesh therewith, is carried by the tally-roll frame which is slid- 65 ingly mounted on the casing of the machine. This casing is removable and when the parts 55 are assembled, if the teeth on gear 542 do

not mesh exactly with the rack teeth 543, then the shaft 539 may yield slightly until, by a relative movement between the teeth, they are brought into proper mesh with each other; likewise, the escapement bar 521 and 70 the lower end of frame 503 may yield outwardly slightly for the same purpose.

The notched bar 39, before described, is provided with an adjustable block 533 having a cam face projection 534, (see Figs. 2 75 and 19) which, in the movement of the typewriter carriage, is designed at the proper moment to operate the bar 531, releasing the plate 544, and permit upward movement thereof to effect an engagement between the 80 clutch members of the carriage return mechanism. This carriage return mechanism for the tally-roll carriage is separate and distinct from the carriage return mechanism for the typewriter carriage, though it derives 85 motion for its constantly driven shaft 535' from the same source of power, to wit, the motor drive for the calculating machine; the constantly driven shaft 535' (see Figs. 2 and 3) has a miter gear 557' at its lower 90 end which meshes with a companion gear 556 on shaft 557 whose forward end is driven by the gears 558 which are in turn driven from the motor.

Tally roll recording mechanism.

95

Referring now to Fig. 1, it will be observed that each of the rack bars 100 has a toothed extension 100^a secured to the rear end thereof, for engagement with the segment 560, there being a segment and its connected type carrying part 561 for each rack. 100 562 are type carried by the type carrying part, said type being riveted or otherwise fixedly secured in position. These type carrying parts have characters, zero, 1, 2, 3, 4, etc., up to 9, in the usual order.

The shaft 271, (see Figs. 1 and 13) on which the side frames 270 are pivoted, which side frames carry the shaft 269 on which the 110 rear totalizer wheels 268 are mounted, is bent up at its middle portion, between its bearings, to permit the segmental racks 560 to pass thereunder. The hub of each segmental rack and type carrying part (560— 115 561) is provided with a shoulder 563 with which coöperates a shoulder on a pivoted type guard carrying member 564. Springs 565 tend to hold the shoulders of these guard carrying members in position against their 120 respective shoulders 563.

566 are thin flexible type guards whose forward ends normally lie over the zero type, in the printing line, and prevent said zero type from making a printing impression on the tally strip. However, whenever any printing segment 561 is operated by movement of its controlling rack 100, it will tilt the guard carrying member 564 forwardly and uncover the type positioned 125 130

in the printing line. The tilting of this guard carrying member 564 forwardly by the actuated type carrying segment, will also operate the guard carrying segment 564 to the right thereof so as to uncover the zero printing type in the printing line. It will be seen by reference to Fig. 12, that each of the guard carrying members 564, except the one in the units column or order of lowest 10 denomination, has a lateral projection 567 extending behind the next adjacent guard carrying member 564 identified with the column of next lowest order. Thus, when any guard carrying member of any order is operated, it will operate all of the other guard carrying members to the right, as seen from the front of the machine, or of lower order, to expose the zero type in the printing line. To illustrate, if \$12.50 was set up on the 20 keyboard and the racks 100 moved forwardly to introduce this number into the selected accumulator, the type-carrying parts of the tally roll printer would be correspondingly positioned to record this number, with the 25 exception of the one identified with the rack of lowest order which would remain unmoved, but whose zero printing type would be exposed in the printing line so that the zero at the right would be printed. All of 30 the type-carrying parts of the tally roll printer of higher denomination to the left of the highest digit in the number being recorded, will remain unmoved and consequently the guards 566 will cover the zero 35 type to the left of the number being recorded and these zeros will not be printed.

The printing impression on the tally strip is made by rocking frame 503 so as to force its platen against the exposed type in the 40 printing line. The tally strip is in front of the platen, as shown in Fig. 1, and the ink ribbon travels over the type in the printing line and under the free ends of the type guards. The method of effecting a printing 45 impression, that is, forcing the tally strip against the type by means of the platen carried by the rocking frame 503, is as follows: The shaft 502, before described, has a groove on its upper side in which is received the 50 lower end of a plate 511, there being slight lost motion of the plate in the groove so as to permit a slight freedom of play necessary in sliding the frame 503 along the shaft. This play or lost motion is also taken 55 advantage of to effect the operation of the tally strip feed rolls, as will presently appear.

At one end of the shaft 502 is fixed an arm 568, which arm has a stop block 569 on its 60 outer end (see Fig. 5) for engagement with the track plate 520. This stop block determines the normal position of shaft 502 and is preferably made adjustable on the arm 568 so as to compensate for irregularity 65 in manufacture. The rock arm 568 extends

through an opening C in the rear wall of the casing, (see Fig. 5), and is provided with a slot 568^a which, as shown in Fig. 5, is normally in position to receive a pin 569^a on the upper end of a bar 570. The 70 lower end of this bar 570 is connected to a cam plate 571, pivoted on the shaft 86 and having a cam slot formed therein for engagement with a stud or pin carried by the cam 266 of the machine which is mounted 75 on shaft 81, which latter is the main operating shaft of the machine and is rocked at every operation of the machine. Thus, whenever the machine is operated, the initial movement of the pin on cam 266, passing 80 through the concentric portion of the slot in cam 571, will maintain the bar 570 practically stationary to enable the digit type 562 to be moved to their printing position, after which and during the final movement 85 of said cam the bar 570 will be depressed to make a printing impression on the tally strip. On the initial reverse movement of cam 266, the bar 570 will be lifted, and during the final movement of the cam, held stationary. The upper end of bar 570 is guided between the forked ends of a bar 572 (see 90 Figs. 4 and 5), which is slotted to receive a screw, whereby the same is variably fulcrumed on the side framing of the machine. 95 This bar 572 is pivotally connected to a rock arm 573 fixed on one end of the sleeve 574 mounted on a cross shaft 575. The opposite end of this sleeve carries a rock arm 576 to which is connected the rear end of a 100 bar 577 whose front end is slotted to receive a screw secured to a bracket on the frame of the machine whereby the front end of said bar is held in position and guided in 105 its movement.

578 indicates blocks adjustably mounted on the notched bar 39 of the typewriter carriage, said blocks having pivoted members 579 whose rear faces are adapted to coöperate with the inclined ends of a T-shaped head 577^a on the forward end of bar 577. It will be observed that there is a straight face between the inclined ends of this T-shaped head. This is to insure proper engagement of the adjustable blocks therewith at the end of each tabulating movement of the tally roll carriage. Unlike the tapes 43, 533, and 552, heretofore described, the bar 577 is not designed to be momentarily vibrated and then returned to its normal position. On the contrary, the blocks 578 are so adjusted that when the tally roll carriage is in its home position, and at the end of each tabulating movement thereof, the bar 577 shall be held in its rearward position. Whenever the bar 577 is forward, the printing mechanism for the tally strip is disabled and thus by the adjustment of blocks 578, this disablement can be effected 110 in any position that the typewriter carriage 115 120 125 130

may occupy, that is, a stationary position wherein other parts of the machine may be operated.

The upper end of bar 570 is held within the forked end of the lever 572 by means of springs 580, (see Figs. 4 and 5). These springs also tend to move the bar 577 forwardly.

When the bar 577 is moved rearwardly, the pin 569^a is moved into the slot 568^a and thus bar 570 is connected to the rock arm 568 and at each operation of the machine the shaft 502 will be rocked.

In order to prevent the pin 569^a from slipping out of its slot, I provide a guard member 581 which is loosely mounted on shaft 502 and which has a finger 581^a at its forward end normally located in front of and below the plane of the pin 569^a. Thus, when the parts are in normal position, the finger uncovers the slot. A spring 582 tends to hold the guard member 581 upwardly at all times. 583 indicates a post carried by the rock arm 568, which post passes through a curved slot in the guard member 581 and carries at its outer end an arm 584 provided with a pin 585, which latter operates the ribbon feeding mechanism of the tally roll attachment, as will hereinafter appear.

The rear wall of the machine forms a stop for the guard member 581 holding it normally in the position shown in Fig. 5 in which the post 583 is located in the upper end of the curved slot thereof while the guard member 581 is depressed. However, when the rock arm 568 is depressed, this post will traverse the slot and eventually contact with the bottom wall thereof, whereupon the guard member will be depressed with the rocking arm and the operation of the ribbon feeding mechanism effected. The depression of rock arm 568 will cause the finger 581^a to close the end of slot 568^a and prevent any displacement of the pin 569^a. In the rocking of the arm 568, the walls of the slot will, in the lowermost position of said rocking movement, be inclined downwardly and the pin would have a tendency to ride down this incline and out of the slot were it not prevented from doing so by the presence of a guard finger 581^a.

When the rock arm 568 is depressed to rock the shaft 502, the platen carried by the frame 503, is brought into contact with the type in the printing line, but the pressure necessary for effecting the printing impression is not exerted upon said platen until the lost motion between the plate 511 and slot in the shaft 502 is taken up. When this lost motion has been overcome, the final pressure is placed upon the platen, this occurring at the last operation of the downward movement of the rock arm 568.

When the rock arm 568 is lifted, it is immaterial whether the frame 503 is first restored to its normal position or whether the lost motion of the plate in the groove is first taken up. In any event, the normally retracted position of the frame is determined by the roller 522 carried by the escapement bar (see Figs. 2 and 3). When the roller 522 contacts with the track plate 520 and arrests the frame 503 in its retracted position, the shaft 502 continues to be rocked, thereby absorbing the lost motion referred to until the stop member 569 engages the track plate 520. This continued rocking movement of the shaft 502 is utilized in line-spacing the tally strip.

Line-spacing the tally strip.

One end of the paper feed roll 509 (the righthand end, as viewed from the front of the machine, see Fig. 3), is provided with a hand-wheel 586 for manual operation. The opposite end of said feed roll is provided with a ratchet wheel 587, (see also Fig. 9). This ratchet wheel co-operates with a spring-pressed centering pin 588 carried by an arm 90 pivotally connected to the frame 503, which centering pin permits the manual rotation of the feed roller 509 in either direction.

To mechanically effect the line-spacing of the paper, I mount a plate 589 (Fig. 9) on the shaft 502, said plate having a slot and pin connection with the frame 503, so as to permit independent movement thereof, and said plate also having a projection which fits into the groove, of shaft 502, but not tightly, permitting a slight independent play of said plate. Plate 589 carries a paper-feeding pawl 590 which is normally held in operative position by a spring 591. A bar 592 (Figs. 2 and 3) is mounted in a bearing provided by one of the brackets 501, said bar being adjustably held in position by means of a set screw 593. This bar is cut away at intervals, as at 592^a, so that whenever said bar is adjusted to locate one of its cut-away portions opposite, or in line with, the paper-feeding pawl 590, (see Fig. 9) said paper-feeding pawl is permitted to engage the ratchet wheel and line-space the tally strip. When, however, the paper-feeding pawl 590 rides upon the bar, as shown by dotted lines in Fig. 9, the vibration of the pawl 590 will be idle. Thus, after a printing impression, and after the frame 503 has been retracted the full measure of its retractive movement, the continued rocking of the shaft 502 in taking up lost motion therebetween and said frame, will rock the plate 589 and vibrate the paper-feeding pawl 590. If the bar 592 is so adjusted as to have a recess in line with said paper-feeding pawl, then the paper-feeding pawl will engage, and by operating the ratchet wheel,

line-space the tally strip; but, if said paper-feeding pawl is riding the bar, its vibration will be idle.

The bar 592 is sufficiently long (see Fig. 2) to hold the paper-feeding pawl 590 in a disabled position throughout the entire travel of the tally roll carriage, except when it occupies that position which may be designated as the extreme left position, when, by the presence of the recess 592^a, line-spacing will be effected. The bar 592 may have a second recess 592^b cut on its opposite side, as shown in Fig. 2, so that by rotating the bar 592, line-spacing of the tally strip can be effected at a point before the carriage reaches its extreme left position. Of course in using the recess 592^b for effecting the line-spacing feed of the tally strip at this point, the blocks should be adjusted accordingly, such as the carriage return block, etc., so as to properly articulate and harmonize the various devices which are controlled by the typewriter carriage.

Feeding the tally roll ink ribbon.

The pin 585 which is vibrated when the arm 568 is rocked, as before described, will, in its descent, strike a lever 593' pivoted at 594 to one of the frame bars of the machine and through extension 593^a thereof rock a plate 595 through the means of a connecting link 596 (see Fig. 8). Plate 595 carries a spring-pressed pawl 597 which operates with a ratchet 598 on a shaft 599 (see Fig. 8). Thus, whenever the frame 568 is rocked to effect a printing impression, the shaft 599 will be rotated a short distance to effect a feeding of the ink ribbon.

Ribbon reverse mechanism.

600^a indicates the ink ribbon which, as shown in Fig. 15, is designed to be wound upon spools 601. Each of these spools has a miter gear 602 connected thereto with which miter gears 603 are designed to alternately engage, depending upon the direction of feed of the ribbon—the ribbon being taken up or wound upon the spool which is being driven. The shaft 599, before referred to, is of such length that when one of these gears 603 is in driving engagement with one spool, the other of said gears is out of driving engagement, and vice versa. Each of the ribbon spools 601 has a hollow core formed in part by a fixed curved wall 604, to which the ends of the ribbon may be secured, and a movable wall 605, the latter being pivoted at one end and connected to a spring 606 which tends to open said wall, as shown at the left in Fig. 15. The free end of this swinging wall carries a pin 607 which extends down through a curved slot in the bottom spool head. In the position of the parts shown in Fig. 15, the pin 607 has been per-

mitted to move outwardly, into the path of 65 a hook on the end of a sliding bar 608. Up to this time, the spool at the right-hand end, in Fig. 15, has been positively driven and exhaustion from the spool at the left-hand side of said figure has permitted the outward 70 swinging of the removable wall and the location of the pin in front of the hook. The continued rotation of the left-hand spool in the direction of the arrow, by the drawing off of the ribbon, will cause the pin 607 to 75 slide the bar 608 leftwardly moving the pinion 603 out of driving engagement with the right-hand spool and the pinion 603, at the left, into engagement with the spool at the left. The spool at the left now becomes 80 the driven spool and in winding up the ribbon thereon, its rotation will be reversed from that indicated by the arrow and the ribbon will in due course fold in the movable wall so as to locate the pin 607 out of 85 the path of the hook on the end of the bar 608. The bar 608 has a hook on its opposite end and the spool at the right side of Fig. 15 has a fixed and movable wall, above described. The bar 608 has an upward extension 90 carrying two collars 609 slidably mounted on shaft 599. Between these collars and members affixed to the shaft are springs 610, one of said springs being interposed between each collar and affixed member of the shaft. The purpose of this yielding connection is to take care of any cocking of the teeth between gears 603 and 602. If the gears are cocked, that is, not brought into proper registration when the bar 608 100 is moved, one of the springs 610 will be compressed until by the next rotation of the shaft 599, the teeth of the gears are brought into proper mesh.

There is a centering device for holding the 105 shaft 599 in its two positions, this consisting of the bar 611, having a roller on its upper end which drops into either one of two V-shaped grooves 612, cut in the shaft 599. A spring 613 holds this roller against the shaft 110 (see Figs. 13 and 15).

The ink ribbon 600^a passes over vertically disposed guide rollers 614 and angularly disposed guide rollers 615. 616 are ribbon guides carried by arms 617 mounted on the 115 shaft which supports the type segments. These ribbon guides are held in their outer position by means of springs 618 and have a slot and pin connection with the arms 617, (see Figs. 10 and 11). The purpose of this 120 is to enable said guides to be pressed inwardly by the platen at each type impression and afterward the guides move the ribbon away from the type so as not to interfere with subsequent movement of the type. The 125 type are of course held stationary during the printing impression as is also the ribbon and the paper feeding mechanism, hereto-

fore described. The ink ribbon is fed just before each type impression, while the line-spacing or paper-feeding mechanism, when in position for paper-feeding operation, is 5 operative only after a type impression.

Eliminating the printing of items on the tally roll.

The machine, as described up to this point, 10 contemplates the printing of items on the tally roll corresponding to the printing of items by the typewriter carriage. Of course, in speaking of "printed items", I refer to those items which are recorded correspond- 15 ing to numbers introduced into the adding mechanism of the machine and which are recorded on the sheet of paper carried by the typewriter carriage. As before stated, whenever the bar 577 is permitted to occupy 20 its forward position, no printing can be effected on the tally roll. Therefore, it is necessary to adjust the blocks 578 to positions wherein the bar 577 will be forced rearwardly at the proper time to cause a 25 record to be made on the tally strip. It follows, therefore, that if the blocks 578 are moved, the bar 577 will not be pushed rearwardly at the end of a tabulating operation, and obviously certain of the blocks 30 may be removed to obviate item printing in certain columns and permit item or total printing in other columns. I will assume, for the purposes of the present description, that it is not desired to print items in any 35 one of the columns on the tally strip, but that it is desired to record only the totals thereof as said totals are yielded from the wheels 119 and 268 and recorded on the sheet of paper carried by the typewriter carriage. To do this, it is necessary to place 40 the printing on the tally strip under control of the two total keys marked "T" and "R. T." (meaning "total" and "rear total").

Referring now to the construction dis- 45 closed in Fig. 21, it will be seen that when the total key is depressed, it will pull forwardly a bar 170, thereby rocking a lever 172. This lever is connected by a link 174 to a bell crank lever 173 having a forward 50 extension which engages a pin on a bar 118, connected to the frame 49, so that when the total key is depressed, the wheels 119 are brought into engagement with the racks 100. The bell crank 173 also has a rearward 55 extension lying under a member 180 of a bell crank which shifts the cams 82-109 (see Fig. 21) moving them in their central or neutral position. The operation of the 60 total key through the link 185 lifts the tap- pet 84 out of the path of pin 83 and thus prevents the lifting of frame 58 which carries the setting-up pins 63.

In my present construction, in addition to carrying out the above operation of the

printing mechanism upon the depression of 65 the total key to record the total on the sheet of paper carried by the typewriter carriage, I also effect the printing of such total on the tally strip. I provide the bar 577 with a shoulder 577^b (see Fig. 2) in front of 70 which lies a bell crank lever 620 (Fig. 21) pivoted to a bracket on the frame of the machine, and which bell crank lever has a slot and pin connection with a bar 621 having a pin 622 on its lower end lying under 75 the forward extension 172^a of bell crank 170. In this manner, whenever the total key is depressed, the bar 621 is pulled downwardly and through the bell crank 620, the bar 577 is moved to the rear so that the 80 printing devices of the tally-roll attachment are brought into operation so as to print the totals of the columns. Of course, the printing of the totals of the columns, as controlled by the total key, just described, 85 can be used in connection with the printing of the items on the tally strip, if desired.

The total key for the rear register wheels 268 may have its extension 304 located over the pin 622 (see Fig. 21), so that when this 90 key is depressed, the total, as represented in the wheels 268, will also be recorded on the tally strip. I do not claim in this application the particular means for shifting the cams 82-109 as the same is more fully 95 shown and described in the French Patent to Hubert Hopkins, No. 383,719, dated January 16, 1908.

I do not deem it necessary to refer in detail to the parts controlled by the rear total 100 key except to say that when it is depressed, in addition to pulling down the link 185, before described, pulling down bar 621, in the present application, causing the wheels 268 to mesh with the racks, shifting the cams 105 82-109 to their second or neutral position, the depression of said rear total key will also lift the levers 102.

I have not herein referred to the operation of subtraction, which is necessary in making 110 out statements where the difference between debits and credits has to be determined, but it is obvious that this can be done in the type of calculating machine shown, in the manner disclosed in the U. S. Letters Patent 115 to Hubert Hopkins, No. 1,118,489, dated November 24, 1914. Indeed, in Fig. 1, I have shown part of the mechanism identified with the multiplying devices of the French patent and the subtracting mechanism of said Hopkins Patent No. 1,118,489.

In Fig. 1, 231 is a sliding bar having a tooth 232 for engagement with the segment 233 whereby the pendants 235 may be positioned over the lifting bars 247. The pendants are each slidable upon the arm 236 of a vertically movable bar 239 having a stepped portion 243 to coöperate with a stop

projection 242 on the rack 100^a, these parts being in all respects similar to those shown and described in said French patent and said Hopkins Patent No. 1,118,489.

5 I have not deemed it necessary in the present application to disclose in detail the tabulating mechanism for the typewriter carriage, as the same may be similar in all respects to that disclosed in U. S. Letters 10 Patent No. 1,027,225, dated May 21, 1912, and No. 1,130,039, dated March 2, 1915, granted upon applications filed by me.

The carriage return mechanism for the typewriter is not illustrated in detail as this 15 may be similar in all respects to that illustrated in Patent No. 1,120,862, dated December 15, 1914, granted upon an application filed by me.

20 The use of the non-print key may not be required, but if such is desired, the mechanism employed in the Hubert Hopkins Patent No. 1,080,694, dated December 9, 1913, or any other desired form, may be employed. It is desirable, however, in the listing of designating characters, such as dates, 25 customers' numbers, etc., to provide means for automatically preventing the accumulation of such numbers as the totals thereof are unnecessary. The mechanism shown in 30 my pending application, Serial No. 759,493, filed April 7, 1913, may be employed for this purpose.

I do not in this application claim the 35 details of the ribbon reversing mechanism, as the same forms the subject matter of United States Patent No. 1,245,637, issued to me November 6, 1917.

What I claim is:

40 1. In an apparatus of the character described, the combination of a grooved rock shaft, a frame slidable upon said rock shaft, means for sliding the frame on the shaft, a platen carried by said frame, and means for rocking said shaft to effect a printing impression by said platen, there being lost motion between said shaft and said platen.

45 2. In an apparatus of the character described, the combination of a grooved shaft, a frame slidably mounted on said shaft and having a lost motion connection therewith, a platen carried by said frame, means for rocking said shaft to move the frame so that said platen will make a printing impression, and paper feeding mechanism which 50 is operated by the rock shaft during the time that it is taking up said lost motion.

55 3. In an apparatus of the character described, the combination of a rock shaft, a tally roll carriage slidably mounted thereon and provided with means for supporting a strip of paper, said tally roll carriage also having a platen for making type impressions, a connection between said carriage and said rock shaft whereby said carriage

is rocked to make said type impressions, 60 means for rocking said rock shaft, and independent stops for determining the home positions of said rock shaft and said carriage.

4. In an apparatus of the character described, the combination of a rock shaft, a tally roll carriage slidably mounted thereon and having a lost motion connection therewith, means for rocking said shaft, a stop for determining the home position of 70 said rocking means, and an independent stop for determining the home or retracted position of said carriage.

5. In an apparatus of the character described, the combination of a rock shaft, a 75 tally roll carriage slidably mounted on said rock shaft and having a lost motion connection therewith, a platen supported by said carriage, means for rocking said shaft to absorb said lost motion and cause said platen to make a printing impression, means for re- 80 tracting the carriage, and a stop for arresting the carriage in its retracted position before said rock shaft reaches its home position.

6. In an apparatus of the character described, the combination of a rock shaft, a tally roll carriage mounted thereon, a platen supported by said carriage, means for operating said rock shaft to cause said platen to make a printing impression, a paper feeding mechanism for the tally roll strip supported by said carriage, and ribbon feeding mechanism, said paper feeding mechanism and ink ribbon feeding devices being 95 dependent in their operation upon the operation of said carriage rocking mechanism.

7. In an apparatus of the character described, the combination of printing type, means for positioning the same, an ink ribbon arranged to be fed over the printing line of said type, a rock shaft, a tally roll carriage having a lost motion connection with said rock shaft, the said carriage having means for supporting a tally strip, paper feeding mechanism for said strip, a platen supported by said carriage, means for rocking said shaft to cause said platen to make a printing impression, said means effecting the feed of said ink ribbon, and the lost motion connection between said shaft and said carriage effecting the feed of said tally strip.

8. In an apparatus of the character described, the combination of printing type, means for positioning the same, a rock shaft, 120 a tally roll frame slidably mounted on said rock shaft, a platen supported by said tally roll frame, and means on said tally roll frame for supporting a roll of tally paper, there being a jointed connection between the 125 platen-carrying section of said frame and the tally roll carrying portion thereof.

9. In an apparatus of the character de-

scribed, the combination of a rock shaft and a tally roll carriage slidably mounted thereon, said carriage comprising two sections each pivotally mounted on said shaft, a platen supported by one of said sections, and a tally roll supported by the other of said sections.

10. In an apparatus of the character described, the combination of a laterally movable paper carriage, a tally roll printing mechanism for making a record of numbers on a tally strip, means controlled by said carriage for determining the recording or non-recording of said numbers on said tally strip, and an independent key for effecting the recording of numbers on said strip.

11. In an apparatus of the character described, the combination of a laterally movable paper carriage for supporting a sheet 20 of paper upon which numbers may be recorded in column order, two or more registers for separately accumulating a number so recorded in the different columns, a separate tally roll recording mechanism, and 25 means whereby the items recorded in the different columns may be reproduced on said tally strip, together with the totals thereof, or the totals only may be reproduced on said tally strip.

12. In an apparatus of the character described, the combination of a tally roll carriage, a rock shaft upon which the same is mounted, means for rocking said shaft to effect recording on the tally roll carried thereby, printing type, means for positioning said printing type, an ink ribbon, feeding mechanism therefore, and means operated by said rock shaft whereby said ink ribbon feeding mechanism is operated. 30

13. In an apparatus of the character described, the combination of printing type, means for positioning the same, an ink ribbon which is fed over the printing line of said type, means for feeding the ink ribbon, said means comprising in part a rock arm, a 45 removable casing, a tally-roll carriage mounted upon said casing, means for operating said carriage to make a record on the tally strip over said type, and means carried by said casing for coöperating with said 50 arm to effect feed of said ink ribbon, said casing and its carried parts being separately removable.

In testimony whereof I hereunto affix my signature this 21st day of March, 1918.

OTTO THIEME
